UNITED STATES PATENT OFFICE.

HENRY G. CONRAD, OF CHICAGO, ILLINOIS.

DEVICE FOR SHARPENING SAWS.

1,087,107.

Specification of Letters Patent.

Patented Feb. 17, 1914.

Application filed May 15, 1911. Serial No. 627,157.

To all whom it may concern:

Be it known that I, HENRY G. CONRAD, a citizen of the United States, residing at Chicago, in the county of Cook and State of Illinois, have invented a certain new and useful Improvement in Devices for Sharpening Saws, of which the following is a specification.

My invention relates to improvements in devices for sharpening saws and is illustrated diagrammatically in one form in the accompanying drawings wherein—

Figure 1 is a plan view of the device with parts removed, Fig. 2 is a front elevation of the device in part section, Fig. 3 is a section along the line 3—3 of Fig. 2, Fig. 4 is a front elevation showing the parts in different relation, Fig. 5 is a detail of the saw.

Like letters refer to like parts throughout the several drawings.

The base A which may be mounted upon the table or bed of a grinding machine or upon a workbench, as the case may be, is adjustably held thereon by the bolts A¹ in the slots A², is provided with the upwardly extending flanges A³ A⁴, which are recessed at A⁵ A⁶ to engage the downwardly and outwardly extending lugs A⁷ A⁸ on the bottom of the sliding table A⁹, and carries the adjustably mounted stop A¹⁰, held in position by the bolt A¹¹ and in opposition to the downwardly extending lug A¹² on the sliding table A⁹. The sliding table A⁹ is provided with the transverse slot B in which is slidably mounted the bolt B¹, terminating at one end in the eye B², and held in position by the lock nuts B³ B⁴. The hollow block B⁵ from which project two parallel lugs B⁶ rotatably mounted on the eye B² by the bolt B⁷ is provided at its bottom with the lug B⁸ in opposition to the slot B. The plug B⁹ which is slidably mounted in the block B⁵ carries the conical surface B¹⁰. The circular saw B¹¹ is held centrally in position on the conical surface B¹⁰ by the cylindrical nut B¹² on the screw B¹³. The arm C is slidably mounted upon the base A being held in position thereon by the bolt C¹ engaging the slot C², and is provided with the upwardly extending hollow cylinder C³ in which is slidably mounted the rod C⁴ held in position by the set screw C⁵ and terminating in the eye C⁶ which supports the table C⁷ held in position thereon by the lugs C⁸ and bolt C⁹. The plate C¹⁰ is adjustably

held upon the edge of the table C⁷ by the screw C¹¹ and is provided with the upwardly extending saw engaging stop C¹².

The emery wheels E and E¹ form a part of any suitable or usual grinding machine 60 which in this case is diagrammatically illustrated by the wheels themselves.

It will be evident that while I have shown in my drawings an operative device, still numerous changes might be made in the size, shape and arrangement of parts without departing materially from the scope of my invention as defined in the appended claim.

The use and operation of my device are as follows: When a circular saw is to be sharpened it is removed from its arbor and placed upon my device being centered upon the conical surface B¹⁰ at the top of the sliding block B⁹ and held upon such surface by the cylindrical nut B¹² which is mounted on the screw B¹³ projecting therefrom. The plug is then dropped into place in the hollow cylinder B⁵ and the cylinder so adjusted in position in the slot B in the sliding table that when the table is carried forward to the end of its excursion, which excursion is limited by the stop A¹⁰ on the base A engaging the lug A¹², the saw tooth will just engage the grinding or sharpening wheel E at the proper point. The adjustable stop C¹², which is mounted on the base, is then so positioned that when the carriage is moved forward the saw will overhang the table C⁷ from which the stop projects and the stop will prevent rotation of the saw beyond that point at which the face of the tooth will be sharpened. When the sharpening of each individual tooth has been completed the table is 90 carried back and the saw rotated until the sharpened tooth is in position to engage the stop and the next tooth is then ground in the same way. When the saw is to be jointed, that is, when the tops of the teeth are to be ground off so as to make all the diameters of the saw equal, a round or flat wheel is substituted for the shaped grinding wheel, is brought into opposition to the saw, and the saw is then rotated allowing the wheel 95 to grind off the face of each tooth. If the teeth are to be ground at an angle, as in the case of a crosscut saw the lock nuts B³ B⁴ carrying the eye bolt B¹ are rotated to raise or lower this bolt thus holding the block B⁵ 100 105 110

at an angle to the table and therefore maintaining the saw itself at the desired angle, as indicated in Fig. 4.

I claim:

5 A saw sharpening device comprising the following elements, a grinding wheel, a base adjustably mounted so as to move to and from the wheel along a line at right angles to its axis, flanges projecting upwardly from the base and shaped so as to each form a track at its upper edge, a slotted table mounted so as to slide laterally on said track and a stop adjustably mounted on the base and a lug downwardly depending from the carriage in opposition to said stop so as to limit the motion of the carriage toward the grinding wheel, a vertically adjustable rod

20 mounted in the slot in the carriage and provided with an eye at its upper end, a saw centering and supporting device pivotally mounted on said eye and resting upon the carriage and engaging the slot therein, a saw supporting device adjustably mounted on the base and adapted to support the saw 25 at a distance from its center when the saw is mounted in position and a tooth engaging guide finger mounted on said saw supporting device and adjacent the grinding wheel substantially as shown and described.

HENRY G. CONRAD.
